CLAIM

I claim the ornamental design for the poppable addition silicone board, as shown and described.

DESCRIPTION

FIG. 1 is a top plan view of a poppable addition silicone board showing my new design;

FIG. 2 is the bottom plan view thereof;

FIG. 3 is a rear elevational view thereof;

FIG. 4 is a front elevational view thereof;

FIG. 5 is a left elevational view thereof;

FIG. 6 is a right elevational view thereof;

FIG. 7 is a top, front, and right perspective view thereof; and,

FIG. 8 is a bottom perspective view thereof.
